UNITED STATES PATENT OFFICE.

HENRY E. MOOMAW, OF CHATTANOOGA, TENNESSEE.

METALLIC ROOFING-SHINGLE.

SPECIFICATION forming part of Letters Patent No. 727,179, dated May 5, 1903.

Application filed February 7, 1903. Serial No. 142,391. (No model.)

To all whom it may concern:

Be it known that I, HENRY E. MOOMAW, a citizen of the United States of America, and a resident of Chattanooga, county of Hamilton, State of Tennessee, have invented certain new and useful Improvements in Metallic Roofing-Shingles, of which the following is a full, clear, and exact description, reference being had to the accompanying drawings, in

10 which—

Figure 1 is a perspective view of the adjacent parts of a series of shingles, showing the manner of overlapping; Fig. 2, a transverse section of one of the detachable lock-seams 15 enlarged; Fig. 3, a similar view slightly modified, and Fig. 4 an edge view of the lower end of one of the shingles.

This invention has reference to that class 20 of metallic shingles which have their adjacent longitudinal edges overlapped and locked detachably together in such manner as to form a gutter or channel, which will serve to prevent the water working under the shingles and will shed it upon the row of shingles next 25 below, the shingles below being alternated with the shingles above, so that the upper channels will discharge their water upon the middle portions of the shingles below.

The object of the present invention is to 30 provide an improved lock-joint which will permit the utmost expansion and contraction of the shingles without unlocking and which will more effectually prevent the rain-water working in at the joints and reaching the 35 roof-boards, as more fully hereinafter set forth.

Referring to the drawings by letters, *b* designates a channel formed in the shingle near its nailing-flange by bending up a portion of 40 the body of the shingle and folding it upon itself, as indicated at *a*, this folded part *a* being bent outward toward the nailing-flange *e*, the mouth of the channel *b* being thereby restricted. Between the channel *b* and the nail-flange *e* are formed two separate ridges or corrugations *c*, running the full length of 45 the shingle and forming a channel or gutter *d* between them, said ridges *c* being formed by simply striking or folding up portions of the body of the shingle. These ridges *c*, as well 50 as the folded part *a*, project above the main

surface of the shingle. The other longitudinal edge of the shingle is provided with a bridge *f*, which when the shingles are interlocked is adapted to rest upon and bridge over 55 the ridges *c* and be substantially flush with the upper side of the folded tongue *a*. The edge of the shingle at *g* beyond this bridge or swell *f* is bent upward, so that when it is inserted in the channel *b* in fastening the 60 shingles together it will spring under the tongue part *a* and will bear up resiliently against its under side, as shown in Fig. 2. As will be observed, when the shingles are interlocked the outer shoulder of the bridge portion *f* bears directly against the inner shoulder of the innermost ridge *c*, these shoulders being preferably made substantially vertical. Depending from the under side of the bridge 65 *f* is a longitudinal drip-flange *h*, which extends the full length of the shingle and depends a short distance into the valley *d*. 70

It will be observed that in light rain-storms the valley *b* will catch and discharge all the water that works in between the edges of the 75 shingles, but in heavy and prolonged storms or when the roof is covered with melting snows there will be a tendency for the water to work up under the spring-tongue past the first ridge *c*. If this occurs, the valley *d* will 80 catch such leakage and properly discharge it, thereby making it a very remote possibility that any water shall reach the roof-boards. To guard against the entrance of water by capillary attraction, I provide the drip-flange 85 *h*, which will collect and discharge into the valley *d* any water that may work in along under the surface of the bridge *f*. This drip-flange *h* is formed by simply depressing a portion of the metal of the shingle centrally 90 of the bridge *f*. The bridge *f* bears firmly upon the ridges *c*, not only in order that a water-tight joint shall be formed at two points, but also in order that the bridge *f* will be firmly supported. It will be observed also 95 that the two ridges *c* and the intermediate valley and bridge will permit the shingles to readily contract and expand without strain and without unlocking. This is an important feature, as shingles of this sort are subjected 100 when in use to the extremes of heat and cold and full provision must be made not only

against buckling, but also against unlocking or unfastening.

At the middle of the lower edge of each shingle a bridge *i* is formed to permit the shingle to straddle the locked joint of the shingles below, and each shingle is preferably strengthened and ornamented by one or more embossings, such as *j* and *k*.

It will be observed that each row of shingles overlaps the upper ends of the row of the next below and that across the overlapped part of each shingle is formed a series of ribs *m*, struck up from the body of the shingle and extending from the bridge *f* at one side to the fold *a* at the opposite side, the lowermost one of these ribs being formed straight and the others being preferably curved and each having its front or lower edge substantially straight or square. These ribs *m* serve as water-dams to prevent the rain-water being blown up under the ends of the overlapped shingles, and to further guard against the water passing up under the shingles and also to assist in holding the shingles in place those portions of the lower edge of each shingle between its central bridge *i* and the lap *a* on one edge and the bridge *f* at the other edge are bent down, as at *l*, these downward-bent parts being adapted to bear against the lowermost rib or dam *m*, as shown most clearly in Figs. 1 and 4. It will be observed that the overlapping shingles rest upon the dams *m*.

If desired, the drip-flange *h* may be omitted, as shown in Fig. 3, without departing from the spirit of my invention.

Having thus fully described my invention,

what I claim, and desire to secure by Letters Patent, is—

1. A main lock-joint for shingles consisting of a locking channel or fold formed in one of the shingles near its nailing-flange and two longitudinal ridges formed in the shingle between said channel and said nailing-flange, a second or supplemental valley or gutter being formed between these ridges, and a locking-tongue formed on the adjacent shingle and adapted to enter said lock fold or channel, this adjacent shingle being provided with a bridge extending longitudinally of the shingle and bridging and resting upon the ridges aforesaid, for the purposes set forth.

2. A lock-joint for roofing-shingles comprising a locking channel or fold extending longitudinally of the shingle near its nailing-flange and a pair of separated ridges extending longitudinally of the shingle between said locking-fold and said nailing-flange, and an adjacent shingle having a locking tongue or flange adapted for insertion in said locking fold or channel and a bridge portion extending across said ridges, this bridgeportion being provided with a depending longitudinal drip-flange coincident with the channel between the ridges.

In testimony whereof I hereunto affix my signature, in the presence of two witnesses, this 3d day of February, 1903.

HENRY E. MOOMAW.
